[57] ABSTRACT

Described are the compounds having the structures:

wherein R represents C₃–C₆ alkyl; aralkyl; hydroxy alkyl; and alkoxy alkyl, and uses thereof in augmenting or enhancing the aroma of perfume compositions, colognes, and perfumed articles (including fabric softener compositions, fabric softener articles, hair conditioners, floor waxes, solid or liquid anionic, cationic nonionic or zwitterionic detergents, and deodorant compositions and deodorant articles), as well as processes for preparing such compounds.

**USE OF NORBORNYL ETHERS IN AUGMENTING
OR ENHANCING THE AROMA OF FABRIC
SOFTENER ARTICLES AND COMPOSITIONS**

This application is a continuation-in-part of application for U.S. Letters Patent Ser. No. 280,275 filed July 6, 1981 now U.S. Pat. No. 4,330,416 which, in turn, is a streamline divisional of application for U.S. Letters Patent Ser. No. 200,012 filed on Oct. 23, 1980, now U.S. Pat. No. 4,311,861 issued Jan. 19, 1982.

BACKGROUND OF THE INVENTION

The present invention relates to substituted norbornene ether derivatives of the genus of compounds having the structures:

wherein R represents C₃-C₆ alkyl; aralkyl; hydroxy alkyl; and alkoxy alkyl, and uses thereof in order to alter, modify or enhance the aroma of consumable materials.

There has been considerable work performed relating to substances which can be used to impart (modify, augment or enhance) fragrances to (or in) various consumable materials. These substances are used to diminish the use of natural materials, some of which may be in short supply and to provide more uniform properties in the finished product.

Long-lasting, fresh, green bean, rose, citrus, petit-grain-like, fruity, anisic, green, raw potato-like, twiggly, herbaceous, sweet, sweaty, green pea-like, chocolate-like, carrot-like and creamy aroma nuances with galbanum topnotes and anther-like and anise-like undertones are desirable in several types of perfume compositions, perfumed articles and colognes.

The perfume use of norbornene alcohol and ester derivatives having the structures:

wherein R₁ is C₁-C₄ alkyl is disclosed in U.S. Pat. No. 3,860,635 particularly at Example XV at column 16 thereof. Such compounds and the synthesis thereof are

also disclosed by Bobyleva, Zh. Org. Kh. Volume 13, No. 10, pages 2085-92, October 1977. In addition, ethers of norbornene derivatives having the structures:

are disclosed as well as the process for preparing same according to the reaction:

in Shield, Can. J. Chem. Volume 49, 1971, page 1142.

U.S. Pat. No. 3,927,116 indicates the utility of certain vinyl norbornyl ethers having the structure:

wherein R₂ represents C₁-C₄ alkyl as being intermediate for the preparation of detergents at column 9 lines 10-15. No indication in U.S. Pat. No. 3,927,116 of the use of such compounds in perfumery, for augmenting or enhancing the aroma of perfumes, perfumed articles and colognes, is suggested either implicitly or explicitly in U.S. Pat. No. 3,927,116.

The compounds of our invention, having the structures:

have unobvious, unexpected and advantageous perfumery properties over any closely similar compounds of the prior art.

BRIEF DESCRIPTION OF THE DRAWINGS

FIG. 1 sets forth the GLC profile for the crude reaction product of Example I containing the compounds having the structures:

FIG. 1(A) is the GLC profile of the purified reaction product of Example I containing the compounds having the structures:

wherein peak 2 on said FIG. 1(A) is the compound having the structure:

and peak 3 on said FIG. 1(A) consists of the compound having the structure:

FIG. 2 sets forth the NMR spectrum for the reaction product of Example 1(A) containing the compounds having the structures:

-continued

10 FIG. 2(A) represents the NMR spectrum for peak 2 of the GLC profile of FIG. 1(A) and consists of the compound having the structure:

20 FIG. 2(B) is the NMR spectrum for peak 3 of the GLC profile of FIG. 1(A) and consists essentially of the compound having the structure:

30 FIG. 3 sets forth the infra red spectrum for the reaction product of Example I containing the compounds having the structures:

45 FIG. 3(A) represents the infra red spectrum for peak 2 of the GLC profile of FIG. 1(A) which peak consists essentially of the compound having the structure:

55 FIG. 3(B) represents the infra red spectrum for peak 3 of the GLC profile of FIG. 1(A) and consists essentially of the compound having the structure:

FIG. 4 sets forth the GLC profile for the reaction product of Example II containing the compounds having the structures:

FIG. 5 sets forth the NMR spectrum for the reaction product of Example II containing the compounds having the structures:

FIG. 6 is the infra red spectrum for the reaction product of Example II containing the compounds having the structures:

FIG. 7 sets forth the GLC profile for the reaction product of Example III containing the compounds having the structures:

FIG. 8 represents the NMR spectrum for the reaction product of Example III containing the compounds having the structures:

FIG. 9 sets forth the infra red spectrum for the reaction product of Example III containing the compounds having the structures:

FIG. 10 represents the GLC profile for the reaction product of Example IV containing the compounds having the structures:

FIG. 11 sets forth the NMR spectrum for the reaction product of Example IV containing the compounds having the structures:

FIG. 12 represents the infra red spectrum for the reaction product of Example IV containing the compounds having the structures:

FIG. 13 is the NMR spectrum for the reaction product of Example V containing the compounds having the structures:

and

10

FIG. 14 sets forth the infra red spectrum for the reaction product of Example V containing the compounds having the structures:

and

15

FIG. 15 represents the GLC profile for the reaction product of Example VI containing the compounds having the structures:

20

FIG. 16 sets forth the NMR spectrum for the reaction product of Example VI containing the compounds having the structures:

25

FIG. 17 sets forth the infra red spectrum for the reaction product of Example VI containing the compounds having the structures:

FIG. 17 represents the infra red spectrum for the reaction product of Example VI containing the compounds having the structures:

10

FIG. 18 sets forth the GLC profile for the reaction product of Example VII containing the compounds having the structures:

15

20

FIG. 19 sets forth the NMR spectrum for the reaction product of Example VII containing the compounds having the structures:

25

30

35

40

FIG. 20 sets forth the infra red spectrum for the reaction product of Example VII containing the compounds having the structures:

45

50

FIG. 21 sets forth the GLC profile for the reaction product of Example VIII containing the compounds having the structures:

55

60

FIG. 22 sets forth the NMR spectrum for the reaction product of Example VIII containing the compounds having the structures:

FIG. 23 sets forth the infra red spectrum for the reaction product of Example VIII containing the compounds having the structures:

FIG. 24 sets forth the GLC profile for the reaction product of Example IX containing the compounds having the structures:

FIG. 27 sets forth the GLC profile for the reaction product of Example X containing the compounds having the structures:

FIG. 28 sets forth the NMR spectrum for the reaction product of Example X containing the compounds having the structures:

FIG. 25 sets forth the NMR spectrum for the reaction product of Example IX containing the compounds having the structures:

FIG. 29 sets forth the infra red spectrum for the reaction product of Example X containing the compounds having the structures:

FIG. 26 sets forth the infra red spectrum for the reaction product of Example IX containing the compounds having the structures:

11

-continued

5

FIG. 30 sets forth the GLC profile for the reaction product of Example XI containing the compounds having the structures:

12

-continued

10

DETAILED DESCRIPTION OF THE DRAWINGS

FIG. 1(A) is the GLC profile for the reaction product produced according to Example I and contains starting material having the structure:

20

and

25

and

30

FIG. 31 sets forth the NMR spectrum for the reaction product of Example XI containing the compounds having the structures:

35

40

and

45

FIG. 32 sets forth the infra red spectrum for the reaction product of Example XI containing the compounds having the structures:

55

and

Reference "1" indicates the peak of this GLC profile which consists of the compound having the structure:

50

Reference "2" indicates the peak of the GLC profile which consists essentially of the compound having the structure:

60

Reference "3" indicates the peak of the GLC profile which consists essentially of the compound having the structure:

65

The instant invention relates to the use for augmenting or enhancing the aroma of perfumes, perfumed articles and colognes of compounds having the generic structures:

5

10

15

either taken alone or in admixture wherein R represents C₃-C₆ alkyl; aralkyl; hydroxy alkyl; and alkoxy alkyl.

These compounds as a group have long lasting, fresh, green bean, rose, citrus, petitgrain-like, fruity, anisic, green, raw potato-like, twiggy, herbaceous, sweet, sweaty, green pea-like, chocolate-like, carrot-like and creamy aroma nuances with galbanum topnotes and 20 anther-like and anise-like undertones.

The compounds of our invention may be prepared by reacting ethylidene norbornene having the structure:

25

with ROH, and alcohol wherein R represents C₃-C₆ alkyl; aralkyl; hydroxy alkyl; and alkoxy alkyl in the presence of a catalyst which is either a mineral acid or a Lewis acid. Examples of mineral acid catalysts are 35 sulfuric acid, phosphoric acid, para-toluene sulfonic acid, methane sulfonic acid and acid ion-exchange resin. Examples of Lewis acid which can be used as catalysts are boron trifluoride etherate, aluminum chloride, zinc chloride, stannic chloride, stannous chloride, zinc bromide, diethyl aluminum chloride, ethyl aluminum dichloride, ethyl aluminum dibromide and diethyl aluminum bromide. The reaction preferably takes place in the presence of an inert solvent such as tetrahydrofuran, toluene or benzene. The reaction may take place in the 45 absence of the inert solvent and in the presence of an excess of the alcohol reactant, the excess of the alcohol reactant being used as the "solvent".

The reaction temperature may vary from about 25° C. up to 120° C. with reflux temperature being preferred. The reflux temperature depends upon the pressure in the reactor and the particular solvent being used as well as its concentration. The mole ratio of acid catalyst to ethylidene norbornene may vary from about 1:99 up to about 1:10. The mole ratio of ethylidene norbornene reactant to ROH alcohol reactant may vary from about 1:1 up to about 1:2 with a mole ratio of 1:1.5 of norbornene: alcohol reactant being preferred. Thus, the reaction to produce the compounds of our invention 60 may be shown thusly:

55

and separate therefrom compounds having the structure:

These compounds, however, may be separated by distillation, extraction and preparative GLC techniques in 40 order to yield separately compounds having the structure:

and separate therefrom compounds having the structure:

In addition, the compounds having the structure:

65

The compounds of our invention are usually prepared in admixture with compounds having the generic structure:

being prepared along with compounds having the structure:

These compounds, however, may be separated by distillation, extraction and preparative GLC techniques in 40 order to yield separately compounds having the structure:

exist in isomeric forms and are produced in admixture. The mixture of these "endo" and "exo" and "cis" and "trans" isomers may be separated from one another by means of standard separation techniques including preparative GLC techniques whereby the individual isomers may be separated and then utilized individually. Structures of these isomers are as follows:

Specific examples of the compounds produced according to the foregoing process and useful for the practice of my invention are set forth in table I below.

TABLE I

Structure of Compounds	Perfumery Evaluation
	A fresh, green bean-like rose, citrus, (petitgrain-like) aroma.
	Produced according to Example I
	A fruity, anisic, green aroma.
	Produced according to Example I
	Produced according to Example II
	Produced according to Example III
	Produced according to Example IV
	Produced according to Example V
	An excellent green aroma.

TABLE I-continued

Structure of Compounds	Perfumery Evaluation
Produced according to Example II	
	A green, raw potato aroma with galbanum topnotes.
and	
Produced according to Example III	
	A long lasting, green, twiggy, fruity and herbaceous aroma.
and	
Produced according to Example IV	
	A sweet, fruity aroma.
and	
Produced according to Example V	
	An excellent green aroma.
and	

TABLE I-continued

Structure of Compounds	Perfumery Evaluation
Produced according to Example VI	
	A green, sweaty aroma.
and	
Produced according to Example VII	
	A green pea-like and green aroma.
and	
Produced according to Example VIII	
	A green and chocolate-like aroma with anther-like undertones
Produced according to Example IX	
	A floral, green and carrot-like aroma.
and	

TABLE I-continued

Structure of Compounds	Perfumery Evaluation
10	Produced according to Example X
	A green, creamy, string bean-like, herbaceous and floral-rosey aroma with anise-like undertones.
and	
20	
25	Produced according to Example XI
30	The norbornyl ether derivative(s) and one or more auxiliary perfume ingredients, including, for example, hydrocarbons, alcohols, ketones, aldehydes, nitriles, esters, lactones, ethers other than said norbornyl ether derivative(s), hydrocarbons, synthetic essential oils and natural essential oils may be admixed so that the combined odors of the individual components produce a pleasant and desired fragrance, particularly and preferably in citrusy and/or green woody and/or piney fragrances. Such perfume compositions usually contain (a) the main note or the "bouquet" or foundation stone of the composition; (b) modifiers which round off and
35	accompany the main note; (c) fixatives which include odorous substances which lend a particular note to the perfume throughout all stages of evaporation and substances which retard evaporation; and (d) topnotes which are usually low boiling fresh smelling materials.
40	
45	In perfume compositions, it is the individual components which contribute to their particular olfactory characteristics, however the over-all sensory effect of the perfume composition will be at least the sum total of the effects of each of the ingredients. Thus, one or more
50	55 of the norbornyl ether derivative(s) of our invention can be used to alter, modify or enhance the aroma characteristic of a perfume composition, for example, by utilizing or moderating the olfactory reaction contributed by another ingredient in the composition.
55	55 The amount of norbornyl ether derivative(s) of our invention which will be effective in perfume compositions as well as in perfumed articles and colognes depends upon many factors, including the other ingredients, their amounts and the effects which are desired. It
60	60 has been found that perfume compositions containing as little as 0.005% of norbornyl ether derivative(s) or even less (e.g. 0.002%) can be used to impart fresh, green bean, rosey, citrus, petitgrain-like, fruity, anisic, green, raw potato-like, twiggy, herbaceous, sweet, sweaty,
65	65 green pea-like, chocolate-like, floral, carrot-like and creamy aroma nuances with galbanum topnotes and anther-like and anise-like undertones to soaps, cosmetics, detergents (including anionic, non-ionic, zwitter-

ionic and cationic solid or liquid detergents) or other products. The amount employed can range up to 70% of the fragrance components and will depend upon considerations of cost, nature of the end product, the effect desired on the finished product and the particular fragrance sought.

The norbornyl ether derivative(s) of our invention are useful (taken alone or together with other detergents in perfume compositions) in detergents and soaps, space odorants and deodorants, perfumes, colognes, 10 toilet water, bath preparations such as lacquers brillantines, pomades and shampoos; cosmetic preparations, such as creams, deodorants, hand lotions and sun screens; powders such as talcs, dusting powders, face powders and the like. As little as 0.25% of the norbornyl ether derivative(s) will suffice to impart an intense green, petitgrain-like, rosey and citrusy notes to citrusy, 15 woody, floral and piney perfume formulations. Generally, no more than 5% of the norbornyl ether derivative(s) based on the ultimate end product is required to be used as is or in the perfume composition.

Furthermore, as little as 0.25% of the norbornyl ether derivative(s) will suffice to impart such aroma to perfumed articles per se, whether in the presence of other perfume materials or whether used by itself. Thus, the 25 range of use of the norbornyl ether derivative(s) of our invention in perfumed articles may vary from 0.25% up to 5% by weight based on the total weight of the perfumed article.

In addition, the perfume composition or fragrance 30 composition of our invention can contain a vehicle, or carrier for the norbornyl ether derivative(s). The vehicle can be a liquid such as a non-toxic alcohol, e.g. ethanol, a non-toxic glycol, e.g. propylene glycol or the like. The carrier can also be an absorbent solid, such as a gum, (e.g. gum arabic), or components for encapsulating the composition by means of coacervation (such as 35 gelatin).

It will thus be apparent that the norbornyl ether derivative(s) of our invention can be utilized to alter, 40 modify or enhance aroma of perfume compositions, colognes or perfumed articles.

Examples I-XI, following, serve to illustrate processes for specifically producing the norbornyl ether derivative(s) useful in our invention.

45

The following examples in general, serve to illustrate specific embodiments of our invention. It will be understood that these examples are illustrative and the invention is to be considered restricted thereto only as indicated in the appended claims. All parts and percentages given herewith are by weight unless otherwise specified.

EXAMPLE I

PREPARATION OF A MIXTURE OF 2-ETHYL-5-ISOPROPYLTRICYCLO[2.2.1.0^(2,6)]HEPTANE and 2-ETHYLIDENE-6-ISOPROPOXYNORBORNANE

55

Reaction:

-continued

Vinylidene norbornene (480 grams) is added over a 90 minute period to a stirred solution of isopropanol (300 grams) and boron trifluoride etherate (12 grams) at reflux (temperature varies from 75° C. to 97° C.). The reaction mass is quenched with 1 liter of water. The organic layer is subsequently washed with 500 ml of 10% NaOH. Distillation through a 1½"×12" Goodloe® packed column affords 651 grams of product (b.p. 75° C. at 5 mmHg pressure).

FIG. 1 sets forth the GLC profile for the crude reaction product of Example I containing the compounds having the structures:

FIG. 1(A) is the GLC profile of the purified reaction product of Example I containing the compounds having the structures:

wherein peak 2 on said FIG. 1(A) is the compound having the structure:

and peak 3 on said FIG. 1(A) consists of the compound having the structure:

FIG. 2 sets forth the NMR spectrum of the product mixture consisting of 2-ethyl-5-isopropyltricyclo[2.2.1.0^(2,6)]heptane and 2-ethylidene-6-isopropoxy-norbornane having respectively, the structures:

FIG. 2(A) sets forth the NMR spectrum for peak 2 of the GLC profile of FIG. 1(A) consisting of the compound having the structure:

FIG. 2(B) sets forth the NMR spectrum for peak 3 of the GLC profile of FIG. 1(A) consisting of the compound having the structure:

FIG. 3 sets forth the infra red spectrum of the product mixture consisting of 2-ethyl-5-isopropyltricyclo[2.2.1.0^(2,6)]heptane and 2-ethylidene-6-isopropoxy-norbornane.

FIG. 3(A) sets forth the infra red spectrum for peak 2 of the GLC profile of FIG. 1(A) consisting of the compound having the structure:

FIG. 3(B) sets forth the infra red spectrum for peak 3 of the GLC profile of FIG. 1(A) consisting of the compound having the structure:

EXAMPLE II

PREPARATION OF A MIXTURE CONSISTING

OF

2-ETHYL-5-ALLYLTRICYCLO[2.2.1.0^(2,6)]HEPTANE AND
2-ETHYLIDENE-6-ALLYLNORBORNANE

Ethylidene norbornene (480 grams) is added over a 90 minute period to a stirred solution of toluene (250 ml), allyl alcohol (267 grams), and BF_3 etherate (15 ml) at reflux. The reaction mass is quenched with 1 liter of water and the organic layer is washed with 500 ml of 10% sodium carbonate. The toluene is removed on a rotary evaporator. The organic solution is distilled through a $1\frac{1}{2}'' \times 12''$ Goodloe R packed column to afford 490 grams of product (b.p. 60° C. at 3 mmHg pressure).

FIG. 4 represents the GLC profile of the crude product (conditions: 150° C. isothermal, $10' \times \frac{1}{4}''$, 10% SE-30 packed column).

FIG. 5 shows the NMR spectrum of the mixture consisting of 2-ethyl-5-allyltricyclo[2.2.1.0^(2,6)]heptane and 2-ethylidene-6-allylnorbornane, respectively having the structures:

-continued

FIG. 6 sets forth the infra red spectrum of the mixture consisting of 2-ethyl-5-allyl tricyclo[2.2.1.0^(2,6)]heptane and 2-ethylidene-6-allylnorbornane.

EXAMPLE III
PREPARATION OF A MIXTURE CONSISTING OF
2-ETHYL-5-(β -HYDROXYETHOXY)-TRICYCLO[2.2.1.0^(2,6)]HEPTANE AND
2-ETHYLIDENE-6-(β -HYDROXYETHOXY)-NORBORNANE

Reaction:Ethylidene norbornene (480 grams) is added over a 4½ hour period to a stirred solution of ethylene glycol (186 grams) and boron trifluoride etherate (15 ml) at 60° C. At the end of this period the resulting organic reaction mass is washed two times with 500 ml of water and washed once with 500 ml of 10% sodium carbonate solution.

The resulting organic layer is then distilled through a 1½"×12" Goodloe ® packed column to afford 168 grams of product (b.p.: 100° C. at 2 mmHg pressure).

FIG. 7 sets forth the GLC profile of the crude reaction product (conditions: 180° C., isothermal, 10'×¼", 10% SE-30 packed column).

FIG. 8 sets forth the NMR spectrum for the reaction product consisting of 2-ethyl-5-(β -hydroxyethoxy)-tricyclo[2.2.1.0^(2,6)]heptane and 2-ethylidene-6-(β -hydroxyethoxy)nорbornane having, respectively, the structures:

FIG. 9 sets forth the infra red spectrum for the product mixture consisting of 2-ethyl-5-(β -hydroxyethoxy)-tricyclo[2.2.1.0^(2,6)]heptane and 2-ethylidene-6-(β -hydroxyethoxy)nорbornane.

EXAMPLE IV

PREPARATION OF A MIXTURE CONSISTING OF
2-ETHYL-5-HEXYLOXYTRICYCLO[2.2.1.0^(2,6)]HEPTANE AND
2-ETHYLIDENE-6-HEXYLOXYNORBORNANE

Reaction:Ethylidene norbornene (480 grams) is added over a two hour period to a stirred solution of hexyl alcohol (510 grams) and boron trifluoride etherate at 95° C. The reaction mass is poured into one liter of water and the organic layer is subsequently washed with 500 mls of a 10% sodium carbonate solution. Distillation through a 1½"×12" Goodloe ® packed column affords 523 grams of product (b.p. 6° C. at 1 mmHg pressure).

FIG. 10 represents the GLC profile for the crude reaction product (conditions: 180° C., isothermal, 10'×¼", 10%, SE-30 packed column).

FIG. 11 sets forth the NMR spectrum of the product mixture consisting of the compounds having the structures:

-continued

5

FIG. 12 sets forth the infra red spectrum of the product mixture consisting of the compounds having the structures:

EXAMPLE VI

PREPARATION OF A MIXTURE CONSISTING
OF2-ETHYL-5-(β -METHOXYETHOXY)TRICY-
CLO[2.2.1.0^(2,6)]HEPTANE AND2-ETHYLIDENE-6-(β -METHOXYETHOXY)NOR-
BORNANE

EXAMPLE V
PREPARATION OF A MIXTURE CONSISTING
OF
2-ETHYL-5-S-BUTYLOXYTRICYCLO[2.2.1.0^(2,6)]
HEPTANE AND
2-ETHYLIDENE-6-S-BUTYLOXYNORBORNANE

Ethylidene norbornene (480 grams) is added over a two hour period to a stirred solution of s-butyl alcohol (444 grams) and boron trifluoride etherate at 85° C. The reaction mass is poured into one liter of water and the organic layer is washed with 500 ml of a 10% sodium carbonate solution. Distillation through a 1" x 12" Goodloe ® packed column, afford 513 grams of product (b.p. 78° C. at 5 mmHg pressure).

FIG. 13 sets forth the NMR spectrum of the product mixture consisting of the compounds having the structures:

Ethylidene norbornene (360 grams) is added to a stirred solution of β -methoxyethanol (304 grams) and boron trifluoride etherate (30 ml) at 60° C. over a two hour period. The reaction mass is then poured into 500 ml of water and washed with a 10% sodium carbonate solution. Distillation through a 1" x 12" Goodloe ® packed column affords 348 grams of product (b.p. 75° C. at 0.3 mmHg).

FIG. 15 sets forth GLC profile of the crude reaction product (conditions: 180° C., isothermal, 10' x 1/4" 10%, SE-30 packed column).

FIG. 16 sets forth the NMR spectrum of the product mixture consisting of the compounds having the structures:

FIG. 17 sets forth the infra red spectrum of the product mixture consisting of the compounds having the structures:

EXAMPLE VII

PREPARATION OF A MIXTURE CONSISTING OF 2-ETHYL-5-ISOAMYLOXYTRICYCLO[2.2.1.0^(2,6)]HEPTANE AND 2-ETHYLIDENE-6-ISOAMYLOXYNORBORNANE

Reaction:

Ethylidene norbornene (408 grams) is added over a two hour period to a solution of isoamyl alcohol (360 grams) and boron trifluoride etherate (30 ml) at 75° C. The reaction mixture is heated at 75° C. for a period of two hours whereupon it is quenched with one liter of water. The reaction mass is then washed with a 10% sodium carbonate solution. Distillation through a 1½"×12" Goodloe® packed column affords 446 grams of product (b.p. 79° C. at 0.4 mmHg pressure).

FIG. 18 represents the GLC profile of the crude reaction product (conditions: 220° C., isothermal; 10'×¼" 10%, SE-30 packed column).

FIG. 19 sets forth the NMR spectrum of the product mixture consisting of the compounds having the structures:

FIG. 20 sets forth the infra red spectrum of the product mixture consisting of the compounds having the structures:

EXAMPLE VIII

PREPARATION OF A MIXTURE CONSISTING OF 2-ETHYL-5-PHENETHYLOXYTRICYCLO[2.2.1.0^(2,6)]HEPTANE AND 2-ETHYLIDENE-6-PHENETHYLOXYNORBORNANE

Reaction:

Ethylidene norbornene (427 grams) is added over a two hour period to a solution of phenylethyl alcohol (379 grams) and boron trifluoride etherate (30 ml). The reaction mass is then heated to 100° C. for 90 minutes. Water (one liter) is added and the reaction mass is washed with a 10% sodium carbonate solution. Distillation through a 1½"×12" Goodloe® packed column affords 192 grams of product (b.p.: 105° C.-128° C. at 0.7 mmHg pressure).

FIG. 21 represents the GLC profile of the crude reaction product (conditions: 220° C., isothermal; 10'×¼" 10%, SE-30 packed column).

FIG. 22 sets forth the NMR spectrum of the product mixture consisting of the compounds having the structures:

2-ethyl-5-(1',3'-DIMETHYLBUTYLOXY)TRICY-
CLO[2.2.1.0^(2,6)]HEPTANE and
2-ETHYLIDENE-6-(1',3'-DIMETHYLBUTYLOX-
Y)NORBORNANE

Reaction:

Ethylidene norbornene (360 grams) is added to a solution of 4-methyl-2-pentanol (408 grams) and boron trifluoride etherate (30 ml) over a two hour period at 45 60° C. The reaction mass is then heated at 75° C. for two hours and quenched in 500 ml of water. The resulting organic layer is washed with 500 ml of a 10% sodium 50 carbonate solution. Distillation through a 1½"×12" Goodloe® packed column yields 236 grams of product (b.p. 70° C. at 0.4 mmHg pressure).

FIG. 24 sets forth the GLC profile of the crude reac- 55 tion mixture (conditions: 220° C., isothermal; 10'×1" 10%, SE-30 packed column).

EXAMPLE XIV

Concentrated liquid detergents (Lysine salt of n-dodecylbenzene sulfonic acid as more specifically described in U.S. Pat. No. 3,948,818, issued on Apr. 6, 1976) with fragrance profiles as defined in Table IV below are prepared containing 0.10%, 0.15%, 0.20%, 0.25%, 0.30% and 0.35% of the substance as set forth in Table IV below. They are prepared by adding and homogeneously mixing the appropriate quantity of substance as set forth in Table IV below in the liquid detergent. The detergents all possess excellent intense aromas as defined according to the profiles of Table IV below, the intensity increasing with greater concentrations of said substance as set forth below in Table IV:

EXAMPLE XVI

PREPARATION OF SOAP COMPOSITION

One hundred grams of soap chips (IVORY®), produced by the Proctor & Gamble Company, Cincinnati, Ohio) are admixed with one gram of the substance as set forth in Table VI below until homogeneous compositions are obtained. In each of the cases, the homogeneous compositions are heated under three atmospheres pressure at 180° C. for a period of three hours and the resulting liquids are placed into soap molds. The resulting soap cakes, on cooling, manifest excellent, long-lasting, warm aromas as set forth in the Table VI below:

TABLE VI

XII(L)	A floral, green and carrot-like aroma.	
	A green, creamy, stringbean-like, herbaceous and floral-rosey aroma with anise-like undertones.	10

In the following examples, Aromox® DMC-W and Aromox® DMMC-W are 30% aqueous solutions of dimethyl cocoamine oxide; and Aromox® NCMDW is a 40% aqueous solution of N-cocomorpholine oxide 15 produced by Armac division of AKZO of Chicago, Illinois.

EXAMPLE XIX

Four drops of one of the substances set forth in Table 20 IX below is added to two grams of Aromox® DMC-W to produce a clear premix. The clear premix is added to 200 grams of CLOROX® with stirring resulting in a clear stable, single phase solution. Sufficient 1 M aqueous NaOH is added to bring the pH of the mixture up to 12.8. The solution remains substantially stable at 120° F. for a period of seven days. When the 5% aqueous sodium hypochlorite solution is used as a laundry bleach, the resulting laundry, on dry-out in an atmosphere of 30 65% relative humidity yields substantially no characteristic "hypochlorite" odor, but does have a faint pleasant aroma as set forth in Table IX below. Furthermore, no such characteristic "hypochlorite" aroma is retained on the hands of the individual handling such laundry in 35 both the wet and the dry states:

EXAMPLE XX

40 Amorox® DMMC-W in various quantities is mixed with 0.1 grams of one of the substances set forth in Table X below. The resulting premixes are then added to 200 grams of an aqueous 5% sodium hypochlorite solution. Sufficient 12.5 M aqueous NaOH is added to bring the pH of the mixture up to 13. The following results are obtained:

Percentage Aromox® DMMC-W	Clarity of hypochlorite solution after addition of premix
0.23%	Clear after three days
0.15%	Clear after three days
0.08%	Initially slightly turbid; two phases exist after three days.

55 When the 5% aqueous sodium hypochlorite solution is used as a laundry bleach, the resulting laundry on dry-out, in an atmosphere of 65% relative humidity, 60 yields substantially no characteristic "hypochlorite" odor, but does have a faint, pleasant aroma as set forth in Table X below. Furthermore, no such characteristic "hypochlorite" aroma is retained on the hands of the individual handling such laundry in both the wet and 65 the dry states:

Each of Examples XIII(A-L) has interesting pine needle oil aromas with various nuances described as follows:

Example	Aroma nuance
XIII(A)	A fresh, green bean-like rose, citrus, (petitgrain-like) aroma.
XIII(B)	A fruity, anisic, green aroma.
XIII(C)	A green raw potato aroma with galbanum topnotes.
XIII(D)	A long lasting, green, twiggly, fruity and herbaceous aroma.
XIII(E)	A sweet, fruity aroma.
XIII(F)	An excellent green aroma.
XIII(G)	A green, sweaty aroma.
XIII(H)	A green pea-like and green aroma.
XIII(J)	A green and chocolate-like aroma with anther-like undertones
XIII(K)	A floral, green and carrot-like aroma.
XIII(L)	A green, creamy, stringbean-like, herbaceous and floral-rose aroma with anise-like undertones.

EXAMPLE XXI

Two grams of Aromox® DMMC-W is admixed with eight drops of one of the substances set forth in Table XI below. The premix is then added with stirring to 200 grams of a 7% aqueous solution of lithium hypochlorite. Sufficient 3 M aqueous LiOH is added to bring the pH of the solution to 13.4. The mixture is then heated to 120° F. and maintained at that temperature

with stirring for a period of 1 week. The resulting solution remains clear in a single phase. When used as a laundry bleach, the resulting bleached laundry, on dry-out in an atmosphere of 50% relative humidity retains a "clean" warm aroma as set forth in Table IX below; whereas without the use of the substance set forth in Table XI below, the bleached laundry has a faint characteristic disagreeable "hypochlorite" aroma.

EXAMPLE XXIV

Four drops of one of the substances set forth in Table XIV below is added to 1.5 grams of Aromox® to produce a clear premix. The clear premix is added to 200 grams of CLOROX® with stirring resulting in a clear stable single phase solution. Sufficient 1 M aqueous NaOH is added to bring the pH of the mixture up to 12.8. The solution remains substantially stable at 120° F. for a period of 7 days. When the 5% aqueous sodium hypochlorite solution is used as a laundry bleach, the resulting laundry on dry-out in an atmosphere of 65% relative humidity yields substantially no characteristic "hypochlorite" odor but does have a faint pleasant warm, long-lasting aroma as set forth in Table XIV below. Furthermore, no such characteristic "hypochlorite" aroma is retained on the hands of the individual handling such laundry in both the wet and the dry states:

EXAMPLE XXIX

SCOURING CLEANSER COMPOSITION

A scouring cleanser composition is prepared in accordance with Example I, at columns 11 and 12 of U.S. Pat. No. 4,193,888, issued on Mar. 18, 1980. To this composition, a substance as set forth in Table XIX below is added at the level of 0.250% as set forth in the Table in said Example I of U.S. Pat. No. 4,193,888 yielding an aroma on using acid cleanser in ordinary circumstances which is quite pleasant and described in said Table XIX as set forth below:

and	
Produced according to Example III	
	A long lasting, green, twiggy, fruity and herbaceous aroma.
and	
Produced according to Example IV	

TABLE XX-continued

	A sweet, fruity aroma.
and	
Produced according to Example V	
	An excellent green aroma.
and	
Produced according to Example VI	
	A green, sweaty aroma.
and	
Produced according to Example VII	
	A green pea-like and green aroma.
and	
Produced according to Example VIII	

TABLE XX-continued

A green and chocolate-like aroma with anther-like undertones

Produced according to Example IX

A floral, green and carrot-like aroma.

and

Produced according to Example X

A green, creamy, string-bean-like, herbaceous and floral-rosey aroma with anise-like undertones.

and

Produced according to Example XI

A floral, green and carrot-like aroma.

and

Produced according to Example X

A green, creamy, string-bean-like, herbaceous and floral-rosey aroma with anise-like undertones.

TABLE XX-continued

and

Produced according to Example XI

Each of Examples XXII(A-L) has interesting pine needle oil aromas with various nuances described as follows:

Example	Aroma nuance
XII(A)	A fresh, green bean-like rose, citrus, (petitgrain-like) aroma.
XII(B)	A fruity, anisic, green aroma.
XII(C)	A green raw potato aroma with galbanum topnotes.
XII(D)	A long lasting, green, twiggly, fruity and herbaceous aroma.
XII(E)	A sweet, fruity aroma.
XII(F)	An excellent green aroma.
XII(G)	A green, sweaty aroma.
XII(H)	A green pea-like and green aroma.
XII(J)	A green and chocolate-like aroma with anther-like undertones.
XII(K)	A floral, green and carrot-like aroma.
XII(L)	A green, creamy, stringbean-like, herbaceous and floral-rosey aroma with anise-like undertones.

What is claimed is:

1. A fabric softening article comprising a non-woven cloth substrate, in contact with said substrate a substrate coating and in contact with said substrate coating and outer coating, said outer coating comprising at least one compound having a structure selected from the group consisting of:

wherein "R" represents C₃-C₆ alkyl; phenethyl; methoxyethyl; cyclohexyl; allyl; and hydroxyethyl and the 50 moieties "R" are the same in each of the molecules, in an amount sufficient to augment or enhance the aroma of the headspace in a dryer on operation thereof when using said article.

2. The article of claim 1 wherein "R" is isopropyl.
3. The article of claim 1 wherein "R" is allyl.
4. The article of claim 1 wherein "R" is hydroxyethyl.
5. The article of claim 1 wherein "R" is n-hexyl.
6. The article of claim 1 wherein "R" is 2-butyl.
7. The article of claim 1 wherein "R" is methoxyethyl.
8. The article of claim 1 wherein "R" is 3-methylbutyl.
9. The article of claim 1 wherein "R" is phenethyl.
10. The article of claim 1 wherein "R" is 4-methyl-2-pentyl.
11. The article of claim 1 wherein "R" is 2-methylpropyl.

12. The article of claim 1 wherein "R" is cyclohexyl.
 13. A fabric softener composition comprising a fabric softener and intimately admixed therewith from 0.25% up to 5% by weight based on the total weight of fabric softener composition of at least one compound having a structure selected from the group consisting of:

wherein "R" represents C₃-C₆ alkyl; phenethyl; hydroxyethyl; methoxyethyl; allyl and cyclohexyl and the moieties "R" are the same in each of the molecules.

14. The composition of claim 13 wherein "R" is isopropyl.

- 98
 15. The composition of claim 13 wherein "R" is allyl.
 16. The composition of claim 13 wherein "R" is hydroxyethyl.
 17. The composition of claim 13 wherein "R" is n-hexyl.
 18. The composition of claim 13 wherein "R" is 2-butyl.
 19. The composition of claim 13 wherein "R" is methoxyethyl.
 10 20. The composition of claim 13 wherein "R" is 3-methylbutyl.
 21. The composition of claim 13 wherein "R" is phenethyl.
 22. The composition of claim 13 wherein "R" is 4-15 methyl-2-pentyl.
 23. The composition of claim 13 wherein "R" is 2-methylpropyl.
 24. The composition of claim 13 wherein "R" is cyclohexyl.
